UNITED STATES PATENT OFFICE

RUSSELL W. BAKER, OF ANDERSON, INDIANA, ASSIGNOR, BY MESNE ASSIGNMENTS, TO DELCO-REMY CORPORATION, OF DAYTON, OHIO, A CORPORATION OF DELAWARE

INSULATION-FORMING MACHINE

Application filed March 15, 1926, Serial No. 94,989. Renewed April 3, 1928.

This invention relates to the manufacture of armatures for dynamo-electric machines and more particularly to the manufacture of parts for insulating the armature core teeth.

5 One object of the present invention is to provide a process and machine by which insulating members of this type may be produced with great rapidity so that the cost of this part of manufacturing an armature will be 10 materially reduced.

Further objects and advantages of the present invention will be apparent from the following description, reference being had to the accompanying drawings, wherein a preferred 15 form of embodiment of the present invention is clearly shown.

In the drawings:

Figs. 1 to 7 inclusive are views partly in section showing different steps in the process 20 of folding a strip of flat insulating paper so as to form an armature core tooth insulating member of the desired shape. These views are taken respectively on the lines 1—1, 2—2, 3—3, 4—4, 5—5, 6—6 and 7—7 of Fig. 10.

25 Fig. 8 is a side view of a strip of insulating material formed by the present invention.

Fig. 9 is a fragmentary view on an enlarged scale of an armature which is insulated by members manufactured by the present invention.

30 Fig. 10 is a plan view partly in section of a machine for carrying out the process illustrated by Figs. 1 to 7 and for cutting the folded strip into the desired lengths.

35 Fig. 11 is a side view looking in the direction of arrow 11 in Fig. 10.

Fig. 12 is an end view in the direction of arrow 12 of Fig. 11.

40 Figs. 13 and 14 are bottom plan and end view respectively of the upper paper folding members shown in Figs. 4, 5, 10 and 11.

Figs. 15 and 16 are top plan view and end view respectively of the lower paper folding member shown in Figs. 2, 3, 4, 5, 10 and 11.

45 Referring to the drawings, one type or form of insulating member which may be produced by the present invention is shown in Figs. 7 and 8. This member designated in its entirety by numeral 20, comprises a web portion 50 which joins the leg portions 22 which

are L-shaped in cross section. These pieces are applied to an armature core indicated by numeral 23 in Fig. 9, in the following manner: A substantially V-shaped strip of insulating material 24 is inserted within each core slot 25 to provide an insulating lining for the bottom of the slot and portion of the sides of the slot which are defined by the shanks 26 of the core teeth. Then an insulating member 20 is placed around each core tooth as shown 55 in Fig. 9 so that its web portion 21 engages the periphery of a core tooth and its leg portions 22 engage the sides of the shank 26 and overlap the sides of insulating pieces 24. Armature coil windings 27 are placed within the 60 slots 25 and these windings will crowd the portions 22 against the sides of the core teeth to cause them to conform to the shape of the shank 26. Since the parts 22 and 24 are separated and overlapping, these parts may slide 65 relative to each other as the windings are applied to the cores, so that these members may adapt themselves to the shape of the core teeth. After the windings have been applied the insulating pieces 20 are severed at the 70 edges 28 of the core teeth so that the superfluous portions 21 may be removed, leaving only the slot lining portions 22.

The mechanism for folding the strip insulation as shown in Fig. 7 will be first described. The machine comprises a base 30 which supports brackets 31, 32, 33, 34, 35 and 36. The brackets 31 and 32 support a U-shaped member 37 (see Fig. 1) having a convex forming surface 38 over which the 80 paper strip 200 is pulled in order to cause it to bend in a convex manner as viewed from the top of the machine. The paper passes from the forming member 37 into a recess 39 provided by a block 40 (see Figs. 2 and 15) 85 which is secured to the brackets 31, 32, 33 and 34. The recess 39 is defined by a horizontal bottom wall 41 and straight converging side walls 42 and 43. As the strip 200 moves toward the left, the side edges will be brought 90 together gradually. Fig. 3 illustrates the position of a section of the strip at the line 3—3 of Fig. 10. The side walls 42 and 43 merge into parallel vertical walls 44 and 45 respectively which define a narrow channel 95 100

having a bottom wall 46 which merges with bottom wall 41 of the recess 49 and is downwardly inclined toward the left as viewed in Fig. 11. The side edges of strip 200 are forced into this narrow channel and against the bottom wall 46 thereof by a folding member 50 attached by screws 51 to the member 40 and provided with a central channel 51 which is a segment of a circle in cross section and diminishes in cross sectional dimensions as the work proceeds from the right toward the left of the machine. When the strip 200 enters the narrow channel defined by the walls 44, 45 and 46 its shape will be approximately as shown in Fig. 4. In this position the arch of its loop is engaged by the top wall of channel 51. As the work progresses from the section line 4—4 to section line 5—5 of Fig. 10 the loop formed by the paper is gradually changed in sectional shape from a vertical ellipse as shown in Fig. 4 to a horizontal ellipse, as shown in Fig. 5. The loop is finally flattened, as shown in Fig. 6, by passing the strip between an upper roller 60 and a pair of lower rollers 61. The roller 60 is provided with flanges 62 which engage the outer sides of rollers 61. Each roller 61 is provided with a knurled, cylindrical periphery 63 and with conical surfaces 64 and 65. The paper is gripped between the cylindrical periphery 66 of wheel 60 and the knurled cylindrical peripheries 63 of the wheels 61. By providing each wheel 61 with the conical surface 65 the sharp bending of the strip 200 at the portions 201 is prevented. As shown in Fig. 6 the side edges 202 of the strip are received by the V-shaped groove 67 defined by the spaced conical surfaces 64.

After the strip passes the rolls 60 and 61 it is fed through channels 70 and 71 provided by guide blocks 72 and 73 respectively. These channels together form a T-shaped channel conforming to the approximately T-shaped cross section of the work when the margins 202 are located contiguously. The guide block 73 is attached to the guide block 72 by screws 74 and block 72 is attached by screws 75 to the bracket 36. The T-shaped aperture provided by the blocks 72 and 73 merges into a T-shaped opening 80 in a shear disc 81 which is attached by screws 82 to the bracket 36. A rotating blade 83 cooperates with the shear disc 81 to sever sections of the folded strip into pieces of the desired length, as shown in Fig. 8. The blade 83 is provided by a rotating bar 84 having a beveled end 85 which, like the blade 83, conforms to the conical surface 86 of the shear block 81. The bar 84 is supported for rotation by a shaft 87 journaled in bearings 88 provided by the bracket 36, and is slidably connected with the shaft by means including a sleeve 89 attached by key 90 to the shaft 87 and secured endwise by a nut 91. The sleeve 89 is provided with a groove 92 co-operating

with a spline 93 attached to the bar 84. A spring 94 located between the bar 84 and a flange 95 carried by the sleeve 89 causes the bar to be yieldingly urged against the shear disc 81.

The forming wheels and the bar are rotated by a mechanism which includes a belt driven pulley 100 upon the shaft 101 which is supported by bearings 103, 104 and 105 carried by brackets 33, 34 and 35 respectively. The shaft 101 is drivingly connected with the wheel 60 a spur gear 106 and a bevel gear 107. The bevel gear 107 meshes with a bevel gear 108 connected with shaft 87 in order that the cutter 83 may be rotated by the pulley 100. The gear 106 meshes with a gear 109 connected with a shaft 110 which is supported by bearings 111 and 112 supported and guided by the brackets 33 and 34 respectively. Each of the bearings 111 and 112 is urged upwardly by a spring 113 so that the wheels 61 will be yieldingly urged toward the wheel 60. In this manner the paper strip will be yieldingly gripped between the rollers as shown in Fig. 6.

A machine may be adapted for cutting insulation pieces 20 of various lengths within certain limits. This is accomplished by substituting for the spur gears 106 and 109 and for the feeding wheels 60 and 61 other gears and wheels of different diameters. If the diameters of the gears and feeding wheels are less than represented in the drawings, the distance from the base 30 to the folded strip as it leaves the feeding wheels will be greater than that represented by Figs. 11 and 12. Therefore, the distance between the base and the guide members 72 and 73 and the guiding slot in the shear disc 81 must be correspondingly increased. This is accomplished by removing the screws 82 which secure the shear disc to the bracket 37, by turning the disc for example, 90° clockwise and then replacing the screws. In this new position of the disc 81 another T-shaped passage 80a will be brought into alignment with the folding mechanism in order to receive the folded material at a different vertical distance from the base 30. The distance from the passage 80a to the center line of the screw holes through which the screws 82 extend is such that when the disc is relocated in the manner described the passage 80a will be adapted to receive the folding material. If the disc 81 is secured by four equidistant screws, the disc may have four passages 80 which vary in distance from the diametrically center lines of the screw holes in the disc. Quite obviously if the disc were secured by the six equi-distant screws 82 the disc could be mounted in six different positions and might be provided with six passages 80. As the block 72 is provided with slots 72a for receiving the screw 75 it may be adjusted vertically in order that the T-shaped passage provided by the blocks 72 and 73 may

be aligned with the passage 80 in the shear disc 81.

It will be noted that the passage 80 is located so that each portion of the folded strip passing therethrough will be oblique to the edge of the blade 83 as it rotates in a clockwise direction, as viewed in Fig. 12. Therefore, during the cutting of the folded paper each portion is adequately supported by the shear block as the blade cuts into it. As the paper is moving while being sheared it may not be severed exactly at right angles to its long dimensions, but this is immaterial since the paper strip is preferably longer than the armature core and its ends will project beyond the end insulation of the core.

While the form of embodiment of the present invention as herein disclosed, constitutes a preferred form, it is to be understood that other forms might be adopted, all coming within the scope of the claims which follow.

What is claimed is as follows:

1. A machine for forming insulation pieces from flat sheet material which comprises means for folding the material; cutting means which includes an apertured shear block through which the material is guided, and a rotary cutter cooperating with the block.

2. A machine such as defined by claim 1, in which the cutting means includes an apertured shear block through which the material is guided, and a rotary cutter cooperating with the block, the block and cutter having engaging surfaces oblique to the line of motion of the strip for the purpose specified.

3. A machine such as defined by claim 1, in which the folding and feeding apparatus includes feeding and folding rolls interchangeable with other rolls of different diameters, and the shear plate included in the cutting means is adjustably mounted and is provided with various holes for receiving the folded strip, in order that the machine may be adapted to form insulation pieces of different lengths.

4. A machine such as defined by claim 1, in which the feeding and folding means comprises means for folding the paper so that the side marginal portions are contiguous and the intermediate tubular portion is uncreased, and feed rollers for flattening the intermediate tubular portion so that it is located in planes at right angles to the planes of the contiguous marginal portions.

5. The method of folding a flat strip of paper to provide a piece having a cross-section characterized by a web portion joining substantially L-shaped flanges, one leg of each flange abutting the web and the other legs contiguous, which consists in bringing the side marginal portions together without creasing the intermediate portion forming a tubular portion, and in flattening the intermediate tubular portion so that it is located

in planes substantially at right angles to the planes of the contiguous side marginal portions.

6. The method of folding a flat strip of paper to provide a piece having a cross section characterized by a web portion joining substantially L-shaped flanges, one leg of each flange abutting the web and the other legs contiguous, which consists in bringing the side marginal portions together to form the paper so that it will be horse-shoe shaped in cross section, then, while maintaining the arms so formed parallel, moving them into closer proximity to each other and forming the curved portion into a vertical ellipse, then by rolling, maintain the arms parallel while gradually changing the vertical ellipse into a horizontal ellipse and then into a flattened loop lying in a plane substantially at right angles to the adjacent parallel flanges.

7. A machine for forming pieces from flat sheet stock, which comprises, means adapted continuously to feed stock into the machine, means for folding the stock, and means for cutting off proper lengths from the folded stock, said means comprising an apertured block through which the stock is fed, and a cutting knife cooperating with said block, both cutting knife and block having engageable cutting edges, oblique to the line of movement of the stock.

8. A machine for forming pieces from flat sheet stock, which comprises folding means having members for folding the stock so that the side marginal portions are contiguous and the intermediate portion is uncreased, feeding means comprising rollers for flattening the intermediate, uncreased portion so that it is located in planes at right angles to the plane of the contiguous marginal portions, and means for cutting off proper lengths of the formed stock.

9. The method of folding a flat strip of paper to provide a piece having a cross-section characterized by a web portion joining substantially L-shaped flanges, one leg of each flange abutting the web and the other legs contiguous, which consists, bringing the side marginal portions toward each other forming a curved intermediate portion, flattening the curved intermediate portion while maintaining the said marginal portion in contiguous relation, said intermediate portion being flattened into a plane transverse to the planes of the side marginal portions.

10. The method of folding a flat strip of paper to provide a piece having a cross-section characterized by a web portion joining substantially L-shaped flanges, one leg of each flange abutting the web and the other legs contiguous, which comprises, simultaneously bringing the side marginal portions toward each other to form a curved intermediate portion, then flattening said curved intermediate portion in a plane transverse to

the marginal portions while maintaining the marginal portions in contiguous relation.

11. A method of folding a flat strip of paper to provide a piece having a cross-section characterized by a web portion joining substantially L-shaped flanges, one leg of each flange abutting the web and the other legs contiguous, which comprises, bringing the side marginal portions together without creasing the consequently arched intermediate portion, then flattening said arched intermediate portion, so that it comprises juxtaposed portions of paper located in planes substantially at right angles to the planes of the contiguous side marginal portions.
12. The method of folding a flat strip of paper to provide a piece having a cross-section characterized by a web portion joining substantially L-shaped flanges, one leg of each flange abutting the web and the other legs contiguous, which comprises, bringing the side marginal portions together to form the paper so that it will be horse-shoe shaped in cross-section, moving the said portions closer together to form the curved part of the paper into a vertical ellipse, rolling the vertical ellipse into a horizontal ellipse and gradually flattening the paper forming said ellipse into a plane lying substantially at right angles to the side marginal portions.
13. The method of folding a flat strip of paper to provide a piece having a T-shaped cross-section which consists of bending the strip to bring the side marginal edges toward each other, forming a U-shaped structure having substantially parallel branches joined by a substantially semi-circular arched portion, then drawing the parallel branches together while holding them substantially parallel the arch being shaped into an ellipse, then while maintaining the branches in juxtaposed, parallel relation flattening the elliptical web portion so that substantially parallel strip portions are provided practically at right angles to the juxtaposed parallel branch portions, then while maintaining the strips in this formation, severing it to provide formed strips of proper length.

In testimony whereof I hereto affix my signature.

RUSSELL W. BAKER.
